WARREN WEBSTER AND COMPANY, A CORPORATION OF NEW JERSEY.

VALVE DEVICE FOR STEAM-HEATING APPARATUS.

No. 800,285.

Specification of Letters Patent.

Patented Sept. 26, 1905.

Application filed December 13, 1904. Serial No. 236,762.

To all whom it may concern:

Be it known that I, JAMES LOGAN FITTS, of Logan Station, Philadelphia, county of Philadelphia, and State of Pennsylvania, have invented an Improvement in Valve Devices for Steam-Heating Apparatus, of which the following is a specification.

In modern steam-heating practice it is usual to remove the air and water of condensation from the radiators, heaters, or coils by the maintenance of a lower pressure or suction in the returns. It is necessary in such systems that means shall be employed to so control the discharge of the air and water that the escape of uncondensed steam may be prevented. Automatic motor-valves are frequently used for this purpose, in which the main outlet for water of condensation is controlled by a motor, operated by the formation of differential pressure when the water accumulates in the valve-body. The air is extracted through a normally open air-vent or passage-way, and when this is closed, either by mechanical means actuated by the water of condensation or by the formation of a water seal, the suction in the outlet creates a lower pressure on one side of the motor and the valve is opened. To prevent the waste of uncondensed steam through this normally open air-vent, it should be made as small as possible, and a very small area is sufficient for the discharge of air. This vent must not, however, be of smaller area than the suction-passage between the motor and outlet, as that would result in the maintenance of differential on the motor, which would hold the valve constantly open. On the other hand, the suction-passage between the motor and outlet must not be as small as would be sufficient simply for the discharge of air, since it must be large enough to enable the air to be extracted sufficiently quickly when the air-vent is closed to effect an immediate response in the motor to the presence of water of condensation. For these reasons it is usually the case that the air-vent is much larger than is necessary for the discharge of air and there is a resulting waste of steam. It is the object of my invention to overcome this difficulty and to enable the air-vent to be reduced to the smallest area necessary for the discharge of the air without affecting the formation of

the differential pressure when the vent is closed and the sensitiveness of the valve.

In carrying out my object I make the air-vent between the inlet and motor-chamber as small as possible and make the suction passage-way between the motor-chamber and outlet of a variable area, which automatically changes when the air-vent is sealed. When the air-vent is open, the area of the suction passage-way does not exceed that of the air-vent, and consequently there is no waste of steam; but when the air-vent is sealed the area of the suction passage-way is immediately increased, so that the required differential can immediately be formed. The means which I employ for thus automatically controlling the area of the suction passage-way is a movable check which is provided with an air vent or opening of an area which does not exceed that of the air-vent between the inlet and motor-chamber. When the latter vent is open, this check closes the suction-passage except for the small vent or opening through which the air passes. When the air-vent is closed, this check is automatically moved or disturbed to an extent sufficient to enlarge the suction-passage and enable the differential to be produced in the motor. When the valve is opened and the water passes out, the water acts upon the check to maintain the enlarged suction-passage until all the water has escaped. The check then closes the suction-passage to its minimum area and as the air-vent is then unsealed the differential in the motor is broken and the valve closes.

The device is extremely sensitive and responds instantly to changes in conditions. It is also very simple in construction and contains no parts that are liable to get out of order.

In the drawings, Figure 1 is a longitudinal vertical section of my valve device, showing the same connected with a radiator-outlet. Fig. 2 is a perspective view of the check for controlling the differential pressure. Fig. 3 is a vertical section of the motor, showing a modification of the check; and Fig. 4 is a similar view illustrating a further modification.

a is the usual valve-body, having an inlet *b* and outlet *c*. As shown, the inlet is connected with the outlet *d* of a steam-radiator *e* and the outlet with the return-pipe *f*. The outlet

- c* is controlled by the cup-shaped motor *h*, which rests upon the seat about the outlet and is provided with a suction-passage *i*, registering with the outlet, but of smaller area: The 5 upper walls of the motor *h* extend up into valve-body within a surrounding wall *j* with a loose piston fit, forming a slight clearance *k* between them and said surrounding wall. This clearance *k* forms the air-vent between 10 the inlet and motor-chamber. In the particular construction shown this surrounding wall *j* is an annular extension of the cap *m*, which is screwed into the upper open end of the valve-body.
- 15 *n* is a small check-valve within the motor *h* closing the passage *i* therein, but leaving a small air passage-way from said orifice to the interior of the motor. In the construction shown in Fig. 1 this check-valve consists of a 20 small disk resting loosely in the base of the motor, and the air passage-way is provided by small nicks *p* in its edge, as is shown more clearly in Fig. 2.

In the construction shown in Fig. 3 the check 25 consists of a small ball *n'* and the air passage-way is provided by small nicks *p'* in the edge of the orifice *i*.

In the construction shown in Fig. 4 the disk 30 *n*² is not nicked on its outer edge, but is provided with a small central tube *p*², which projects down through the orifice *i* and outlet *c* and forms the small air passage-way.

The area of the check or disk *n* must be materially greater than that of the outlet *c*. In 35 the construction shown in the drawings they are in the ratio of one to four.

When the valve-body is substantially free 40 of water or condensation, the motor will remain upon its seat and the clearance *k* between the walls of the motor *h* and the surrounding wall *j* will be unsealed. The air may then pass from the inlet *b* through the vent or clearance *k*, air passage-way *p*, and suction-passage *i* to the valve-outlet *c*. The passage-way thus 45 afforded may be made very minute—just sufficient to permit the escape of the air without any appreciable waste of steam. When, however, water or condensation accumulates in sufficient quantity to rise into and seal the 50 vent or clearance *k*, this free passage for the air will be closed, and the air will then be drawn from the upper side of the motor by the suction or lower pressure in the return. Owing to the very small size of the air passage-way *p*, however, the differential pressure which 55 could thus be created would be formed too slowly to make the motor respond as quickly and to open the outlet *c* as fully as is desirable, and it is for this reason that the check *n* is 60 employed.

The extraction of the air from the space above the motor after the formation of the water seal disturbs the light check *n* to a sufficient extent to increase the opening to the

discharge of air beyond that afforded by the 65 nicks *p*. This slight disturbance and resulting increase in the suction-opening permits the air to be more quickly exhausted from the space above the motor and results in a much quicker opening of the valve than could otherwise be obtained. The instant the motor *h* is raised from its seat to any appreciable extent the water will start to flow through the outlet *c*, and as it passes out will surge up to some extent through the orifice *i* into the motor *h*, 70 and acting on the check *n* will continue to disturb or agitate it to such an extent that the greater suction-opening will be maintained and the motor will remain elevated as long as water is passing. As the area of the clearance *k* is less than that of this enlarged suction-opening, the differential will not be destroyed even after the water has fallen sufficiently to unseal the clearance, since the air will be extracted faster than it can flow in 75 through the very small space afforded by the clearance *k*. As soon as the water passes out the check *n* comes to a state of rest, and the air-opening then being that afforded by the small nicks *p* the equilibrium of pressures 80 will be restored and the motor will descend upon its seat. I am thus able to use a very minute passage-way *p* for the discharge of air when the valve is closed, which would be wholly inadequate for the creation of the differential pressure necessary to produce a 85 quick action of the motor and to enlarge that passage-way by the movement of the check the instant the water seal is formed, so as to afford a suction-opening of sufficient size. 90

Without the check *n* the motor would remain open, since the air would be extracted from above the motor faster than it could pass in through the clearance *k*. The check *n*, while reducing the suction-opening to a size 95 that will enable the motor to close when the clearance *k* is unsealed, permits that opening to be increased to the larger size when the clearance is sealed. 100

Such water as passes through the clearance 110 *k* into the motor or enters it by the surging action referred to will drain out through the small passage-ways *p*.

The operation of the checks shown in Figs. 3 and 4 is similar to that described. In the 115 construction shown in Fig. 3 a light ball *n'* is used, and when the passage-way *k* is unsealed the air is extracted through the small vent afforded by the nicks *p'* in the orifice, and when the passage-way *k* is sealed the ball is 120 disturbed and the larger opening is afforded.

In the construction shown in Fig. 4 the air is extracted through the small tube *p*², when the passage-way *k* is unsealed.

What I claim as new, and desire to secure 125 by Letters Patent, is as follows:

1. A valve device for heating systems, consisting of a valve-body having an outlet, a

pressure-motor controlling said outlet and having an air passage-way communicating therewith, and a movable check controlling said air passage-way and also having an air passage-way of an area much less than that of the air passage-way of the pressure-motor, said valve device being provided with a further air passage-way between the upper side of the pressure-motor and the inlet side of the valve-body, adapted to be sealed by an accumulation of water of condensation.

2. A valve device for heating systems consisting of a valve-body having an outlet, a pressure-motor controlling said outlet and having an orifice communicating therewith, and a movable check controlling said orifice and having an air passage-way of an area much less than that of said orifice, said valve device being provided with an air passage-way between the upper side of the pressure-motor and the outlet side of the valve-body, adapted to be sealed by an accumulation of water of condensation.

3. In a valve device for heating systems, the combination of a valve-body having an outlet, a pressure-motor controlling said outlet and having an orifice communicating therewith, the upper walls of the motor extending up within a surrounding wall carried by the valve-body with a slight clearance between adapted to be sealed by an accumulation of water of condensation, and a movable check controlling said orifice and having an air passage-way of much less area than said orifice.

35 4. In a valve device for heating systems, the combination of a valve-body having an outlet, a pressure-motor controlling said outlet and having an orifice communicating therewith, the upper walls of the motor extending up within a surrounding wall carried by the valve-body with a slight clearance between adapted to be sealed by an accumulation of water of condensation, and a movable check controlling said orifice consisting of a loose disk arranged over the orifice and provided with an air passage-way of much less area than said orifice.

5. In a valve device for heating systems, the combination of a valve-body having an outlet, a pressure-motor controlling said outlet and having an orifice communicating therewith, the upper walls of the motor extending up within a surrounding wall carried by the valve-body with a slight clearance between adapted to be sealed by an accumulation of water of condensation, and a movable check controlling said orifice consisting of a loose disk arranged over the orifice and having a nicked edge to form a small air passage-way.

50 6. In a valve device, the combination of a valve-body having an outlet, a cup-shaped pressure-motor controlling said outlet and having an orifice communicating therewith, and its upper walls extending up into a sur-

rounding wall carried by the valve-body with 65 a slight clearance between, and a loose check within said motor controlling said orifice and having a small air passage-way.

7. In a valve device, the combination of a valve-body having an outlet, a pressure-motor 70 controlling said outlet and operated by the differential pressure on the inlet and outlet sides thereof, one side of said pressure-motor communicating with said outlet, and means controlled by the passage of water through 75 said outlet to control the area of the communication between said pressure-motor and the outlet side of the valve-body.

8. In a valve device, the combination of a valve-body having an outlet, a pressure-motor 80 controlling said outlet and operated by the differential pressure on its opposite sides, one side of said motor communicating with said outlet, and also with the inlet side of the valve-body by a passage-way adapted to be sealed 85 by an accumulation of water of condensation, and means actuated by the passage of the fluids through said valve device to control the area of the communication between the pressure-motor and the outlet. 90

9. In a valve device, the combination of a valve-body having an outlet, a pressure-motor controlling said outlet and operated by the differential pressure on its opposite sides, one side of said motor communicating with said 95 outlet, and also with the inlet side of the valve-body by a passage-way adapted to be sealed by an accumulation of water of condensation, and a check located at and nearly but not entirely closing the communication between said pressure-motor and the outlet and adapted to be actuated by the passage of the fluids through 100 said valve device.

10. In a valve device, the combination of a valve-body having an outlet, a pressure-motor 105 controlling said outlet and operated by the differential pressure on the opposite sides, one side of said motor communicating with the inlet side of the valve-body through a passage-way adapted to be sealed by an accumulation 110 of water of condensation, and also with the outlet by an opening of an area substantially greater than the area of the communication with the inlet side, and a movable check controlling said opening to the outlet and having 115 an air-opening of an area not greater than that of the communication with the inlet side, said check being arranged to be moved by the passage of the fluids through said valve-body 120 to enlarge the air passage-way to the outlet when the communication to the inlet is sealed.

11. In a valve device, the combination of a valve-body having an inlet and an outlet, a pressure-motor controlling said outlet operated by a differential pressure, one side of the 125 motor communicating with the inlet side of the valve-body through an air-vent of limited area adapted to be controlled by the accumu-

lation of water of condensation in the valve-body, and also with the outlet side through a passage-way of variable area, and means actuated by the passage of the fluids through the 5 valve to vary the area of said passage-way to the outlet when the communication between the motor and the inlet is closed.

In testimony of which invention I hereunto set my hand.

J. LOGAN FITTS.
